UNITED STATES PATENT OFFICE.

GEORGE WILLIAM MASCORD, OF LONDON, ENGLAND, ASSIGNOR TO
ROBERT HOE, OF NEW YORK, N. Y.

REEL-CARRYING APPARATUS FOR WEB-PRINTING PRESSES OR OTHER MACHINES.

SPECIFICATION forming part of Letters Patent No. 769,660, dated September 6, 1904.

Original application filed July 7, 1902, Serial No. 114,701. Divided and this application filed October 3, 1903. Serial No. 175,707. (No model.)

To all whom it may concern:

Be it known that I, GEORGE WILLIAM MASCORD, a citizen of Great Britain, residing at 5 The Crescent, Church Road, Barnes, London, S. W., England, have invented certain new and useful Improvements in and Relating to Reel-Carrying Apparatus for Web-Printing Presses or other Machines, of which the following is a specification.

10 This invention relates to reel-carrying apparatus for use in web-printing presses and other machines, as described in the specification of my prior application for Letters Patent of the United States, Serial No. 114,701, filed the 7th of July, 1902.

The invention has for its particular object to provide reel-carrying apparatus with independent carrying-frames, so that the carrying-frames may be independently rotatable 20 to bring new reels into position for passing through the machine.

The invention is illustrated in the accompanying drawings, in which—

Figure 1 illustrates in elevation and partly 25 in section a reel-carrying apparatus constructed according to the invention, while Fig. 2 is a similar view showing a modification of the invention.

In carrying the invention into effect in its 30 application to a rotary web-printing press the apparatus provided according to the invention is mounted in the rear thereof, as illustrated in Figs. 1 and 2 of the drawings forming part of my said prior application.

35 The carriers are provided, as illustrated in Fig. 1, in sections d^1 d^5 , the respective sections being formed of a rectangular shape and provided with arms on each side, while the lower parts of each section d^1 may be pro-

40 vided with pivots d^6 , lying within holes d^7 , formed in the upper part of the next section, such as d^5 , a ball-race being formed between the opposing parts, such as d^1 d^5 , so that each section may be rotated independently of the

45 others where it is required to present one or a number of new reels only of the series. Similarly the carrier may be mounted upon

a vertical spindle, such as l , in which case the respective pairs of reels may be carried by means of lateral carrying-arms m , which 50 are formed integral with bearing-bosses, such as n n , by means of connecting-arms p , as illustrated. Bearing-bosses, such as q , are fixed upon the spindle l , and ball-bearings are provided between the bearing-bosses q and 55 the bearing-bosses n , so that the carrier may be readily swung round when a new reel is to be presented in position.

In Fig. 2 the spindle l is shown as carried in a journal-bearing and a top bearing r ; but 60 the spindle l may instead be carried by means of lateral brackets secured to the frame of the press, while, similarly, the bearing-bosses q instead of being fixed to the spindle l may also be carried in lateral brackets, so that 65 thus they may serve for supporting the reel-frames as well as for supporting the spindle l .

Various modifications in structure and arrangement will readily suggest themselves to those skilled in the art, and I do not, therefore, need to describe such here. Moreover, if found necessary or desirable, the carrier may be mounted so as to be movable forward and away from the machine. 70

It is obvious that the supporting carrier or 75 frame may be provided to carry sets of two, three, four, or any other number of reels, as may be required. It is, however, in general preferred to arrange the reels in pairs, as 80 illustrated in the figures. Such an arrangement could be utilized for carrying, for example, two relatively narrow reels, one of which could be mounted in front and out of line with the other, the two passing into the machine 85 as one web.

What I claim as my invention, and desire to 90 secure by Letters Patent, is—

1. A reel-carrier comprising a plurality of superimposed independently-rotatable frames, each comprising an upright portion 90 having oppositely-projecting arms, provided with suitable bearings for the reels, substantially as described.

2. A reel-carrier comprising a base-plate,

an upright rotatably supported thereon and having oppositely-projecting arms provided with suitable bearings for the reels, a second upright rotatably supported on said first upright and also having oppositely-projecting arms provided with suitable bearings for the reels, substantially as described.

In testimony whereof I have hereunto signed my name to this specification in the presence of two subscribing witnesses.

GEORGE WILLIAM MASCORD.
